UNITED STATES PATENT OFFICE.

KURT WANDEL, OF NEW YORK, N. Y., ASSIGNOR, BY MESNE ASSIGNMENTS, TO ARKELL SAFETY BAG COMPANY, OF NEW YORK, N. Y., A CORPORATION OF NEW YORK

APPARATUS FOR MAKING STRETCHABLE PAPER.

Application filed January 19, 1920. Serial No. 352,491.

To all whom it may concern:

Be it known that I, KURT WANDEL, a citizen of Wurttemberg, who have declared my intention of becoming a citizen of the 5 United States, and resident of New York city, county of New York, State of New York, have invented an Improvement in Apparatus for Making Stretchable Paper, of which the following description, in connection with the accompanying drawings, is a 10 specification, like characters on the drawings representing like parts in each of the several views.

This invention relates to the manufacture 15 of paper that is made stretchable by crêping or crinkling so as to render it better adapted for wrapping, packing, case lining and like uses. The invention is carried out with the use of a suction box or device associated with 20 the roll from which the paper is crêped in a manner developed from my earlier application Serial No. 346,066, filed Dec. 19, 1919. It has long been recognized as desirable to provide a wrapping or lining paper that is 25 stretchable in both directions, i. e., both transversely and longitudinally of the web, but so far as I am aware no practicable method or means for attaining this end has hitherto been devised. I have found that 30 by the employment of a specially designed suction box in combination with a special crêping roll and doctor, the latter equipped with corrugations or like formation, the paper may be crinkled or crêped so as to be 35 stretchable to a very substantial degree in both directions. In accordance with my invention this desirable double crêping effect may be produced in the paper without requiring the same to be previously soaked or 40 saturated with moisture as has been hitherto considered necessary and the invention is also applicable to the crinkling of waxed or asphalted paper, and also in the treatment of freshly made paper, i. e., as an adjunct of the paper mill. The foregoing and 45 other objects and advantages of the invention will more fully appear from the following detailed description, and the distinctive features of novelty will be there- 50 after pointed out in the appended claims.

Referring to the drawings:

Fig. 1 is a side elevation of an apparatus embodying the invention;

Fig. 2 is a plan view thereof;

Fig. 3 is an elevation showing a preferred 55 form of my improved crêping roll and the novel type of suction box associated therewith, portions thereof being broken away;

Fig. 4 is a transverse section on line 4-4 60 of Fig. 3;

Fig. 5 is an elevation showing a portion 65 of the crêping roll and illustrating the special form of doctor co-operative therewith;

Fig. 6 is a fragmentary detail view showing 70 a portion of the crêping roll in longitudinal section and on an enlarged scale; and

Fig. 7 is a view showing in elevation and 75 also in edge view a sample of the paper produced by the invention and illustrating the novel type of crêping thereof.

10 indicates an upright frame-work equipped with spaced apart ring bearings 11, 12 in which are mounted the ends of the hollow crêping roll or drum 13. This roll presents a corrugated outer surface throughout its intermediate and operative portion but its end portions are smooth as indicated at 13^a to fit into the bearings 11, 12. This hollow roll may be rotated in any suitable manner, this 15 being accomplished as shown by a belt 14 engaging one end of the roll and driven by an electric motor 15. The paper to be treated is shown as supplied from a roll R which is mounted on supports 16 and the paper web W is thence led around a guide roll 17 and through a moistening tank 18 passing around a roll 19 therein up on to the crêping drum, though at this point it is to be clearly understood that the use of this 20 wetting tank 18 is not necessary and that the paper may be either moistened to a greater or less extent or waxed, or otherwise impregnated just before the crêping, or it may be crêped entirely dry by the apparatus to 25 be described. The crêping drum 13 as already stated presents an operative peripheral surface that is corrugated in sinuous curves from end to end, i. e., it is formed with a series of spaced apart circumferential 30 grooves alternating with ribs, the peaks of which ribs and the valleys of the grooves are of curving outline, as indicated at 13^b. The drum is also produced with a multiplicity of relatively small perforations there- 35 through throughout the operative extent thereof indicated at 13^c, the size and character of these perforations being determined 40 by the character of crêping required and also

by the character of the papers to be handled by the machine. The interior surface 13^a of the drum 13 is smooth and cylindrical. This surface is engaged by a specially formed 5 suction box 20, the edge of which engaging the cylindrical surface 13^a may be equipped with a suitable rubber or like packing 20^a to make a tight joint and prevent the waste and loss of the suction effect. This suction 10 box is shown as equipped with supporting projections 20^b at the ends thereof which may be mounted in upright extensions 21 of the frame-work and engaged by compression coil springs 22 which constantly press the 15 suction box upward into engagement with the cylindrical surface of the roll. This suction box presents an edge 20^c adjacent the crêping point of substantially the full width of the doctor and of the paper web being 20 crêped. Backward from this edge 20^c the box converges rapidly at each side as indicated at 20^d towards a central point 20^e which is intermediate the length of the roll and a substantial distance angularly back of the 25 crêping point, e. g., as shown about one hundred twenty degrees, though this particular extent of the suction box backward is to some extent illustrative and may be varied according to requirements. The 30 suction box is equipped with any suitable means for creating a vacuum in the chamber 20^h thereof which vacuum will be operative upon the inner surface of the crêping roll and thence through the perforations of the 35 roll upon the paper thereon. For this purpose I show a suction pipe 23 leading to a suction pump 24 this typifying any suitable source of suction or partial vacuum which may be varied and regulated according to 40 requirements. The doctor 25 co-operative with the corrugated surface of the roll 13 is also of special form. The operative edge of this doctor consists in a series of teeth or projections 25^a, the ends of which are rounded 45 and the spaces therebetween concaved so that the serrated edge thus presented fits nicely upon the corrugated surface of the crêping roll as the doctor is pressed thereagainst at a more or less oblique angle as 50 usual. The doctor 25 is shown as mounted on a pivot 26 on a bracket 27 of the frame-work and held down yieldingly against the crêping roll surface by a tension spring 28. The crinkled paper C as it is cleared from 55 the crêping roll by the doctor is shown as wound on to a receiving roll R' mounted on bearing standards 29.

In operation the paper web is led onto the roll 13, said roll and the width of the paper web being substantially greater than the 60 maximum width of the suction box which is located equi-distant from the ends of the roll. The paper first passes over the apex 20^g of the rearward converging portion of the suction box, it being noted that this apex 65 20^g is opposite the central groove of the roll. This causes the paper web to be drawn closely to the roll midway of the width thereof while the portions at either side are still free to move transversely inward, i. e., 70 toward the longitudinal center of the roll. This transverse drawing in of the paper web from both sides is occasioned by the suction at the central portion causing the paper to be drawn into the corrugations at the central 75 part of the roll. As the paper moves forward it comes over progressively wider portions of the suction box so that the web is drawn down into the corrugations and hence contracted laterally, progressively toward 80 the sides of the web, the outer side parts of the web which are not yet drawn into the grooves of the drum being still free to be drawn in since they are not yet under the influence of the suction. In this way the 85 paper is drawn in from both sides simultaneously and made to conform to the grooved surface of the drum as it reaches the crêping point. Thereupon the toothed doctor 25 engaging and clearing the paper 90 from the roll crinkles it back on itself in the usual manner while at the same time setting and preserving the corrugations or crinkles resulting from the described transverse contraction of the paper,—i. e., the corrugations 95 resulting from the drawing in of the paper on to the drum are converted into a partial longitudinal crêpe or crinkled effect which combined with the usual transverse crinkling produces a zig-zag wavy effect in the 100 paper as indicated in Fig. 7. The paper thus crinkled is stretchable in substantial degree both transversely of the web and lengthwise thereof and is thus much more immune from 105 breakage under local strains than any paper can be which is crinkled one way merely as heretofore usual, it being further noted that this capability of stretching widthwise of the paper tends to secure the paper against 110 breakage in the direction in which it is weakest and hence has hitherto been most apt to break even though crêped in the hitherto usual manner. I am aware that the 115 invention may be embodied in other specific forms without departing from the spirit or essential attributes thereof, and I therefore desire the present embodiment to be considered in all respects as illustrative and not restrictive, reference being had to the appended claims rather than to the foregoing 120 description, to indicate the scope of the invention.

Having described my invention, what I claim as new and desire to secure by Letters Patent is:

1. Apparatus for making stretchable paper, comprising a hollow rotatable drum having perforations therethrough throughout the operative extent thereof, a suction box associated with said drum to create a 130

suction through said perforations, and a doctor co-operative with said drum, the operative surface of said drum having a series of transverse corrugations therein, and said suction box converging backwardly from a point adjacent said doctor to a substantial angular distance around the drum.

2. Apparatus of the kind described, comprising a hollow rotatable drum having apertures therethrough at intervals throughout the operative extent thereof, a suction box mounted within said drum adapted to exert suction through said apertures, and a doctor co-operative with said drum, said suction box converging from each side towards the longitudinal center of said drum backwardly from said doctor through a substantial angular extent of the drum, said drum having a series of sinuous corruga-

20 tions on its operative surface and said doctor

having a serrated edge fitting said corrugations.

3. Apparatus for making stretchable paper, comprising a hollow rotatable drum presenting sinuous corrugations on the operative surface thereof and having perforations therethrough at intervals, a suction box mounted within said drum and operative through said perforations, and a doctor having an operative edge formed to fit said corrugated drum surface, said suction box having a forward portion adjacent said doctor and of approximately the width thereof, and thence converging backwardly from each side toward the longitudinal center of the drum through a substantial angular extent thereof for the purpose stated.

In testimony whereof, I have signed my name to this specification.

KURT WANDEL.
